UNITED STATES PATENT OFFICE.

ARCHIE FRASER MALEY, OF TRAIL, BRITISH COLUMBIA, CANADA.

ELECTRIC STEAM HEATER.

Application filed March 17, 1926. Serial No. 95,465.

My present invention appertains generally to improvements in the art of portable heaters and specifically to a steam electric heater of this character, as described in the present 5 specification and illustrated in the accompanying drawings.

The principal object of this invention is to provide a heater of this character including means for utilizing electric energy in conjunction with a portable radiator, to generate steam and heat, the latter for ordinary compartment or household heating purposes.

Broadly, my invention comprises a radiator including two main sections, namely a steam generating section and a condensing section, which are partitioned at the bottom, having at this extremity an intercommunicating opening. An electrical heating element is located near the bottom of the steam section 10 of the radiator. Water is contained in both said sections, there being just sufficient to completely immerse said heating element, before it is energized. When heated, the water surrounding the heating element is converted 15 into steam, which rises and passes out of the top of the steam section of the radiator, into the adjoining condensing section, in which the temperature of the steam is reduced, due to radiation, the same condensing into water, 20 which flows through the small opening at the bottom of this section into the adjoining steam generating section about the heating element to be again converted into steam.

Other objects and advantages of my invention will become apparent from a perusal of 35 the following specification read in conjunction with the annexed drawing, which is a sectional elevation illustrating an acceptable form of the invention.

The radiator in which I carry my invention into practice is preferably of the ordinary type used in connection with household water heating systems apart from the fact that it is a heating unit per se and is mounted upon 40 casters or the equivalent to facilitate shifting of the same. The radiator comprises, broadly, two principal sections indicated at A and B, the former constituting the steam generating section, the latter the steam condensing section. These sections are interconnected at the tops thereof by the passage indicated at C. At the lower extremities where the principal sections A and B are connected together, the intercommunicating opening, 45 such as commonly found in radiator sections of this type, is closed off to a considerable ex-

tent by means of a partition plate 3. This partition plate is securely held between the meeting parts of the principal sections A and B and extends downwardly across the inter- 60 communicating opening, so as to leave only a comparatively small opening D through which condensed water in the lower extremity of the B sections can pass into the lower extremity of the A sections, as the water around the heating elements, hereinafter mentioned, in the A sections is converted into steam. The partition plate 3 divides the steam condensing section from the steam generating section in such a manner that steam generated in the 70 steam generating section cannot pass through the lower intercommunicating opening from the steam generating section to the steam condensing section. Such steam generated must pass up through the sections forming the 75 steam generating sections A, through the passage C to the steam condensing sections B. The opening D is designed for intercommunication of water from the steam condensing section to the steam generating section below 80 the normal water level of these two principal sections.

A heating element 4 is mounted in the lower part of section A of the radiator, the same being provided with a variable heat switch 85 5 for determining the amount of current delivered to the heating element.

In order that the level of the water contained within the radiator may at all times be easily determined, I provide a water gage 90 6. The upper end of this water gage is provided with a flared mouth 7, through which water may be poured into the radiator.

It is of course to be understood that the radiator may be provided with additional 95 appurtenances necessary for efficient and safe operation.

In use, the water contained within the section A of the coil is converted into steam due to energization of the heating element 4. 100 This steam rises and flows through the opening C into section B of the radiator, where the steam is condensed into water due to the lower temperature of this section of the radiator. The water collecting in the bottom of this 105 section of the radiator flows through the small opening D about the heating element 4 and is again converted into steam. Before the heating element 4 is energized, the water level should be such that the water will just completely cover this heating element.

Obviously, in the commercial adaptation of

my invention, minor changes in the details of construction may be resorted to with advantage, without departing from the spirit of the invention and the scope of the claim as hereininafter set forth.

What I claim as new is:—

In a device of the character described, comprising a plurality of radiator sections suitably supported together, a portion of said sections comprising a steam generating chamber, the remainder of said sections comprising a steam condensing chamber, an intercommunicating opening to allow steam to pass from the top of said generating chamber to the top of said condensing chamber, a water-

return opening from the bottom of said condensing chamber to the bottom of said generating chamber, an electric heating element positioned in said generating chamber in close proximity to the bottom thereof and a partition retained intermediate the lower meeting walls of the sections of the portions of the radiator forming said condensing chamber and said generating chamber, said partition extending downwardly across said water-return opening to a depth below the normal water level in the said generating chamber.

In testimony whereof, I affix my signature.

ARCHIE FRASER MALEY.
